CLAIM

The ornamental design for an electromagnetic localizer, as shown and described.

DESCRIPTION

FIG. 1 is a bottom perspective view of my new design for an electromagnetic localizer;

FIG. 2 is a bottom perspective view;

FIG. 3 is a first side perspective view;

FIG. 4 is an opposite side perspective view;

FIG. 5 is a third side perspective view;

FIG. 6 is a fourth side perspective view; and,

FIG. 7 is a top perspective view.

The broken lines represent a portion of the system associated with the electromagnetic localizer and form no part of the claimed design.
